X-RAY APPARATUS

Application filed July 8, 1931, Serial No. 549,384, and in Germany July 8, 1930.

This invention relates to improvements in X-ray apparatus and has particular reference to a Roentgen tube holder.

An object of the invention is to provide an improved Roentgen tube holder of a simple construction which is X-ray proof and fully protected against high voltage.

A further object is to provide an adequate holder for Roentgen tubes of small dimensions, which are now used in the art and which are protected against high voltage to such an extent that grounded bodies may be safely arranged in a close proximity to their discharge zone.

Another object of this invention is to improve the insulating properties of Roentgen tube holders by providing them with light and thin cables insulated for voltage ranging from 100 kv. to 200 kv., which have not been used for this purpose heretofore and which comprise metallic braidings capable of being grounded.

Yet another object of this invention is to provide an easily movable Roentgen tube holder, wherein means for cooling the anticathode are arranged within the casing.

Still another object is to provide a Roentgen tube holder, wherein only a small current flows to the earth, this being achieved by arranging very long helically wound cooling tubes acting as resistances within the holder.

The above and other objects will appear more clearly from the following detailed description when taken in connection with the accompanying drawing, which illustrates a preferred embodiment of the inventive idea.

In the drawing an apparatus constructed in accordance with the invention is shown in vertical section.

As shown, the apparatus comprises a Roentgen tube 3 closely surrounded on all sides by porcelain insulators 1 and 2 provided with screw threads at their ends near the middle of the tube. The insulators 1 and 2 are threaded onto a metal member or cylinder 4 provided with corresponding screw threads 5 and covering a part of the insulators situated opposite the middle of the Roentgen tube. A metallic conductive X-ray window 6 is used for transmitting X-rays emanating

from the anticathode of the tube. Porcelain tubes 7 and 8 form a continuation of the insulators 1 and 2 in the proximity of the anode and cathode of the Roentgen tube and are supported in their positions with respect to the latter by means of stays 9 and 10. High voltage cables comprising cores 11, insulating servings 12 and metallic braidings 13 are arranged within the tubes 7 and 8, the cable leading to the cathode of the Roentgen tube being connected with a plug box 14 adapted to receive plug contacts 15 of the cathode covering 16 and thus being adapted to supply the working current and the heating currents to the cathode. The cable leading to the anode of the tube is connected with the contact body 17 which is connected with the anode by means of a resilient spring 25, the opposite ends of the two cables being connected with a properly insulated high-voltage current supply at a wall of the X-ray room.

The exterior surfaces of the two insulators 1 and 2 containing the Roentgen tube are completely covered with a layer 26 consisting of a conducting material electrically connected with the metal cylinder 4 and the metallic braidings 13 of the two cables. The whole system is grounded and the cables are connected with the current supply in such a way that beginning with the place where the cables enter the X-ray room, all the parts of the apparatus having a high voltage are separated by a grounded metallic layer from the exterior.

We prefer to make this layer out of a metal which absorbs X-rays, for instance, lead, which may be used where protection against X-rays is needed, the lead being applied by means of the spraying process known in the prior art. It is also possible to make the apparatus X-ray-proof by providing additional porcelain masses either on the total exterior surface of the apparatus or in parts thereof.

The anode is cooled by means conveying the cooling substance through the grounded connecting cylinder 4 to the anticathode tube 19, said means comprising a connecting branch 21 and a tube 27 made out of an insulating material and shown by broken lines in the

drawing. The cooling substance is preferably led out of the apparatus by an outlet tube 22 surrounding the above inlet tube 27. Due to the fact that the branch 21 is grounded, the cooling substance must have insulating properties, as for instance, oil or compressed air, or the cooling tubes situated between the anticathode and the metal cylinder 4 must have a very high resistance.

10 The Roentgen tube 3 is provided with a glass covering 18 which increases the insulating properties of the apparatus to such an extent that no short circuits can arise between the interior of the Roentgen tube and the 15 grounded metal parts. The diameter of the Roentgen tube used in connection with this apparatus is comparatively small, so that the whole device is light and can be easily moved from place to place.

20 As shown in the drawing, the insulating tubes 7 and 8 are arranged in such a way that they converge towards the middle of the Roentgen tube holder, so that the two cables can be easily handled. We prefer to support 25 those cables at a convenient distance from the Roentgen tube holder, for instance, in the middle between the wall and the container and thus make the device easily movable.

We claim:

30 1. In an X-ray apparatus, a Roentgen tube, insulators partially enclosing said tube, the exterior surfaces of said insulators being covered by a metal layer, means comprising a metal member for connecting said insulators, insulating tubes connected with said insulators and carrying high-voltage cables connected with said Roentgen tube, and means for cooling the anode of said Roentgen tube, the last-mentioned means being situated within said insulators and comprising 40 connections projecting through the first-mentioned connecting means.

45 2. In an X-ray apparatus, a Roentgen tube, insulators partially enclosing said tube, the exterior surfaces of said insulators being covered by a metal layer, means comprising a metal member for connecting said insulators, insulating tubes connected with said insulators and carrying high-voltage cables 50 connected with said Roentgen tube, and a plurality of tubes for cooling the anode of said Roentgen tube, the last-mentioned tubes having ends projecting through said connecting means.

55 3. In an X-ray apparatus, a Roentgen tube, insulators partially enclosing said tube, the exterior surfaces of said insulators being covered by a metal layer, means comprising a metal member for connecting said insulators, each one of said insulators comprising 60 a tubular projection forming an integral part of said insulator, and high-voltage cables connected with said Roentgen tube, each one of said cables being carried by a 65 separate projection.

4. In an X-ray apparatus, a Roentgen tube, two insulators enclosing the ends of said tube, the exterior surfaces of said insulators being covered by a metal layer, means comprising a metal member for connecting said insulators, each one of said insulators comprising a tubular member forming an integral part of said insulator and projecting towards the middle of the apparatus, and high-voltage cables connected with said 70 Roentgen tube, each one of said cables being carried by a separate projection.

5. In an X-ray apparatus, a Roentgen tube, insulators partially enclosing said tube, the exterior surfaces of said insulators being covered by an X-ray proof metal layer, and means comprising a metal member for connecting said insulators, each one of said insulators comprising a tubular projection forming an integral part of said insulator, and high-voltage cables connected with said 80 Roentgen tube, each one of said cables being carried by a separate projection.

85 6. In an X-ray apparatus, a Roentgen tube, insulators partially enclosing said tube, the exterior surfaces of said insulators being covered by a metal layer, means comprising a metal member for connecting said insulators, each one of said insulators comprising a tubular projection forming an integral part of said insulator, high-voltage 90 cables connected with said Roentgen tube, each one of said cables being carried by a separate projection, and a metal braiding surrounding each one of said cables and electrically connected with the external metal 95 layer of said insulators.

In testimony whereof we have affixed our signatures.

KARL NIEMANN.
WERNER ZEYSS.
